UNITED STATES PATENT OFFICE.

JAMES R. MCWANE, OF BIRMINGHAM, ALABAMA.

MEANS FOR SUPPORTING CORES IN MOLDS IN THE MANUFACTURE OF TUBULAR CASTINGS.

Application filed December 12, 1924. Serial No. 755,511.

This invention relates to means for supporting cores in molds for elongated tubular castings.

An object is to provide supports for cores of elongated form, such as are used in the manufacture of cast iron pipe or other tubular castings, so as to prevent the core from sagging at the intermediate portion thereof, due to the weight of the core bar, or from moving upwardly or laterally under the influence of the molten metal flowing into the mold, during the step of pouring.

Another object is to provide supporting means for this purpose which may be readily applied in position.

A further object is to provide supporting means which will not interfere with the separation of the cope from the drag, after casting, and which may readily be drawn from the sand of the drag section together with the finished pipe or other casting.

A full and complete understanding of the invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified, so long as such changes or modifications mark no material departure from the salient features of the invention, as pointed out in the appended claims.

In the drawings, in which similar reference characters designate corresponding parts throughout the several figures:—

Figure 1 is a plan view of a lower or drag section of a double pipe flask, the same having the cores in position, the improved means for preventing lateral movement of the cores being shown in plan;

Figure 2 is a side elevation of the complete flask and showing portions of the means for preventing vertical movement of the cores;

Figure 3 is an enlarged, transverse sectional view through the flask;

Figure 4 is a fragmentary vertical, longitudinal section, drawn on the same scale as Figure 3;

Figures 5, 6 and 7 are detail views of the bracket for supporting the means for preventing lateral movement of the cores;

Figure 8 is a detail perspective view of one

of the pins used for preventing vertical movement;

Figure 9 is a transverse sectional view of the cast pipe or the like, after the several supporting pins have been removed therefrom, shown ready for rewelding;

Figure 10 is a view illustrative of the manner of re-welding the pipe to close the holes left therein by the removal of the supporting pins.

In the manufacture of pipe or other similar castings, in the horizontal method of casting the same, it is ordinarily necessary to insert chaplets around the core, at intermediate points along its length to prevent the same from sagging or moving in any direction, and such chaplets, which are merely pieces of metal, are necessarily left embedded in the pipe and are impossible to remove, often causing leakage especially in the case of high pressure water pipe. Reference is made in this connection to my prior Patents, Nos. 1,486,778 and 1,492,517.

The improved means for supporting the core herein shown and described act in the same manner as the chaplets, to prevent vertical or lateral movement of the intermediate portions of the core, but said means may be withdrawn from contact with the finished pipe and the resultant holes may be readily welded to make the pipe water-tight, even under high pressure.

In the drawings there is shown a flask for the manufacture of cast iron pipe according to the horizontal method of casting, and comprising a lower or drag section 1, and an upper or cope section 2 adapted to be superimposed thereon; the two sections having complementary lugs 2^a for the reception of suitable clamping means to lock the sections together.

The drag section is adapted to have the half of a mold 3 formed in sand therein, and the other half of the mold 4 is formed in the upper or cope section, suitable, transversely disposed gates 5 formed in the sand in the drag communicating with a central longitudinal channel 5^a therein to pass the molten metal at different points along the length of the mold into the same. The sand in the cope section is also formed in a series of sprue holes 6, communicating with said channel 5^a, and adapted to pass the molten metal thereinto preferably from a multiple-lipped ladle capable of carrying sufficient metal

for pouring several flasks and of pouring the same uniformly and rapidly, such arrangement providing for a more uniform and rapid distribution of the metal throughout the 5 length of the mold. See my Patent No. 1,535,676.

As shown in Figure 1, the sand cores 7, carried by suitable tubular core bars 8, are placed in the lower half 3 of the mold in 10 exact longitudinal alinement therewith, the exposed ends of the core bars serving to support the same but, because of the elongated nature of the cores for forming pipe, especially of the smaller diameters of pipe, the same 15 tend to sag of their own weight at the intermediate portion thereof, and also tend to be floated by the inflowing molten metal, or to be forced outwardly, as in a double flask for forming two pipes at once, by reason of the 20 course of the metal through the lateral gates 5; and it becomes necessary to guard against such movement of the core by some such means as chaplets or the more advantageous means herein employed.

25 At a central point of the lengths thereof, the cope and drag sections 1 and 2 are provided with openings 9 formed in the walls of the same, and in vertical alinement with the longitudinal axes of the cores 7. Flanking 30 each of these openings are side walls or flanges 10 arranged flush with the top and bottom edges of the cope and drag respectively and having aligned openings constituting wedge seats 11, for the reception of wedges 12 of ordinary tapered form. See Fig. 4.

Pins 13 (Fig. 8) formed of suitable metal, and having their outer portions substantially square in cross section to slidably fit the 40 said openings 9, are adapted to be inserted therein and held by said wedges 12. The inner end portions 14 of the pins are somewhat reduced and round in cross section, the same having a slight taper towards their inner ends, where they are provided with more 45 abruptly tapered terminals 15.

The outer ends of the square portion of each pin is reduced to form a shoulder 16, which is slightly inclined, as shown in Figures 4 and 8, so that by gently driving the 50 wedge in the proper direction a longitudinal movement will be imparted to the pin to cause the same to move inwardly toward the core 7.

Each core bar 8 is provided throughout its 55 length with the usual vent holes and at the center thereof each is equipped with an upper, lower and outer retaining lug 15^a of tapered and dove-tailed form as shown in Figures 3 and 4, said taper extending longitudinally of the core bar. A metallic button 60 or block 16^a, having a suitable tapered and dove-tailed seat on its underside, is adapted to be slipped onto the lug 15^a to detachably hold the same in place so that when the core is being pulled from the finished pipe, after 65 the latter is allowed to cool the buttons or

blocks 16^a will be freed from the lugs, and the core bar will slip more readily through the hardened and burned sand within the pipe and become freed therefrom, the blocks falling out of the pipe along with the sand 70 when the said pipe is tilted and shaken to loosen the sand. This is substantially the same as disclosed in my former Patent No. 1,486,778.

The inner ends of the upper and lower 75 pins 13 are adapted to bear against the outer faces of the blocks 16^a which are exactly flush with the outer surface of the sand core 7, so that the continuity thereof is not broken, and the inner, abruptly tapered ends 15 of 80 said pins traverse the molding or casting space as clearly shown in Figure 3 of the drawings.

The abutting longitudinal edges of the cope and drag sections are each provided with 85 registering, transverse grooves 17 located opposite the outer blocks or buttons 16^a, and adapted to receive a pin 18 preferably of smaller diameter than the pins 13. It has been found in practice that an ordinary wire 90 nail of proper dimensions to give the required strength is a practical and economical form of such a pin, for the purpose of preventing outward movement of the core when the molten metal is poured.

Attached to each side of the lower or drag section is a bracket 19 (Fig. 3) held in position by bolts 20 at the center of the flask, and adapted to be overhung by the outer ends or heads of the pins or nails 18, the said bracket having a shelf or horizontal outwardly-extending plate 21. As best shown in Figs. 5, 6 and 7, lug 22 is formed on the upper face of the shelf 21, and adjacent to the inner edge of the same, said lug having a transverse groove 23 for the exposed end of the pin or nail to rest in, in addition to the afore-said groove 17 in the edge of the drag section. The shelf is further provided at its outer or free edge with spaced lugs 24, arranged at either side of the end of the pin or nail and having their inner faces undercut, as at 25 to provide a seat for a tapered wedge 26, having a correspondingly beveled edge and an inner straight edge to abut 115 against the head of the pin or nail 18, and force the same inwardly against the outer blocks 16^a. Each pin or nail 18 also has its inner end tapered where traversing the casting space, similarly to the pins 13 so that 120 they may be readily withdrawn from their embedded connections with the finished pipe, after the latter is partially cool.

In assembling the mold and the core supporting means, the drag section 1 is first 125 placed upon the molding machine in an inverted position, or similarly to the normal position of the cope section, that is to say, with the normal bottom of the drag uppermost. The lower pins 13 are then placed in position 130

through the openings 9 in the drag section, with the tapered ends 15 fitting in seats or depressions formed in the tubular pattern of the molding machine, and the lower wedges 12 are loosely placed in position to hold said pins. The sand is now rammed in around the pattern and around the pins 13, after which the patterns are lowered from the sand through the usual stripping plate, leaving the 5 half 3 of the mold and the gates 5 and channel 5^a formed therein, the sand serving to hold the pins 13 in proper position. The drag is then inverted and placed upon the casting floor, as shown in Figure 3, with the tapered 10 ends 15 of the pins extending substantially the proper distance into the half-round mold. While the upper or cope section 2 is being operated on in the same manner to form the half 4 of the mold, and the sprue holes 6 15 therein, the cores 7 with the blocks 16^a in place are positioned in the drag section, the lowermost block 16^a contacting with the tapered end of the lower pin 13. Now the outer or side pins or nails 18 are placed in the 20 grooves 17 and 23 of the drag section, the sand being carefully removed or depressed for the purpose so that none may fall in the casting space, the inner tapered end of said pin or nail abutting against the outer blocks 25 16^a and the wedges 26 are then loosely introduced in their seats. The cope, with the pins 13 in position therein, is now brought and placed carefully over the core and the drag, with the edges thereof in exact alinement with 30 the drag, and the groove 17 therein fitting over and receiving the upper portion of the side pins or nails, and the upper pins 13 resting on the upper pads 16^a, whereupon the aforesaid clamping means are applied to the 35 several pairs of complementary lugs 2^a to hold the flask together. The wedges 12 and 26 are then carefully driven in to tighten the contact between the several pins and blocks on the core bar, and it will be seen that neither 40 sagging nor the action of the inflowing metal will act to depress, float or force the core bars to move outwardly.

After the pouring of the metal, the casting is allowed to partially cool, when the said 45 clamps are knocked off and the cope section is lifted off, the upper pins 13 readily passing down through the openings 9 thereof and through the sand of the cope, while being held by their connections with the pipe where the tapered ends 15 traverse the same. The pipe, with the core and core bar therein, is then lifted off of the drag, carrying therewith the upper pins 13 the lower pins 13 which 50 readily pass through the openings 9 in the drag, and through the sand of the drag, and also carrying the pins or nails 18, the wedges 26 having been loosened. The several pins 55 may easily be removed by hand from their attachments to the pipe, thus leaving the pipe as shown at 28 in Figure 9, with the several 60

tapered holes 29 therein at the center only of the said pipe.

The said holes may be easily, quickly and economically closed or filled by a welding process, and a simple method of doing the same has been illustrated in Figure 10 of the drawing. After the core bars and sand are removed from the pipes, the same are rolled along a runway 30 and over an open fire to preheat, to the proper temperature, the area to be welded, to prevent undue strains in the pipe when cooling after the welding, it having been learned from experience that welding the pipe, without pre-heating the same at the area to be welded, results in a weakening of the pipe, when shrinkage takes place. The pre-heating obviates this disadvantage by giving a more uniform temperature throughout the body of the pipe, and consequently a more uniform cooling. After passing over the fire, the preheated pipes are rolled along to an operator standing between the tracks of the runway and in an advantageous position to weld the holes at the centers thereof. After a pipe is welded, the operator may sit in a seat or swing 31 supported from overhead, and by raising his legs, the welded pipe may pass beneath him to be tested and coated, the operator immediately standing again to treat 95 the next pipe.

From the foregoing it will be seen that a simple, cheap and efficient means has been provided for supporting the core bars of molds for making elongated castings without the necessity for using chaplets, said means effectually preventing any movement of the core within the mold during the pouring of the metal.

What is claimed is:—

1. The combination of a pipe mold having a core bar, and means for preventing deflection of the core bar in the pipe mold, comprising a pin having a reduced inner end, said pin being adapted to be inserted through the flask to bear on the core bar, the said reduced end traversing the mold space to be removably embedded in the pipe but not to enter the bore of the pipe and means for locking the pin to maintain its contact with the core bar.

2. Means for supporting an elongated core bar, comprising at least three pins adapted to pass through lateral openings in the flask sections and to bear on the core bar, and means for locking the pins in such engagement to hold the core bar against upward, downward or lateral movement due to the effects of the inflowing metal or to sagging of the core.

3. Means for supporting core bars, comprising upper pins adapted to be passed downwardly through the cope section of the flask to bear on the core bar, means for locking said pins to prevent said bar from floating on the inflowing metal, lower pins adapt-

ed to be passed upwardly through the drag section to bear beneath the core bar, and means for locking said lower pins to prevent said bar from sagging under its own weight.

- 5 4. Means for supporting core bars, comprising upper pins adapted to be passed downwardly through the cope section of the flask to bear on the core bar, means for locking said pins to prevent said bar from floating 10 on the inflowing metal, lower pins adapted to be passed upwardly through the drag section to bear beneath the core bar, means for locking said pins to prevent said bar from sagging under its own weight, side pins 15 adapted to be passed inwardly between the cope and drag sections to bear on the outer sides of the core bar, and means for locking said pins to prevent outward movement of the core bar caused by the metal flowing from 20 the inner sides.

5. A flask for making cast iron pipe and other tubular articles comprising, in combination, a cope; a drag; a core including a core bar mounted on the flask coaxially with the mold provided on the cope and drag; and means to prevent side deflection of the core arising during pouring of the metal, said means comprising a metallic member which enters the flask laterally thereof and is in contact at its inner end with the core bar; and a locking device to hold said member securely in such contact; said metallic member being of relatively small diameter where traversing the molding space so that it may be removed 30 from the casting before it cools without leaving a large hole in the casting.

6. Means for supporting cores for tubular castings in flasks having cope and drag sections provided with openings above and below the core and with registering grooves in their longitudinal meeting edges, wedge seats carried by the sections at the openings and grooves, vertical, oppositely disposed pins passing through the openings and bearing 40 on the core bar to prevent vertical movement thereof, horizontally disposed pins passing through the grooves and bearing on the core bar to prevent outward movement thereof, and wedges adapted to be driven into the seats against the pins to lock the same in position.

7. Means for supporting cores for tubular castings in flasks having cope and drag sections provided with openings above and be-

low the core and with registering grooves in 55 their longitudinal meeting edges, wedge seats carried by the sections at the openings and grooves, vertical, oppositely disposed pins passing through the openings and bearing on the core bar to prevent vertical movement thereof, horizontally disposed pins passing 60 through the grooves and bearing on the core bar to prevent outward movement thereof, and wedges adapted to be driven into the 65 seats against the pins to lock the same in position, said vertical and horizontal pins having tapered inner ends where traversing the casting space to be removably embedded in the casting.

8. Means for preventing upward, downward or lateral movement of the intermediate portions of elongated cores in molds, comprising vertical and horizontal pins having shoulders adapted to pass through openings 70 in the flask sections and bear on blocks removably carried by the core bar, said blocks having their outer faces flush with the outer surface of the core sand, the outer ends of 75 said pins being exposed exterior of the flask sections, wedge seats provided on the flask sections adjacent to the openings, wedges adapted to be driven into the seats and against the shoulders of the pins to hold the same against the flask, said pins having their inner ends tapered where traversing the casting space and bearing on said blocks so as to 80 be readily removed from the casting for finally welding the holes.

9. Means for preventing transverse movement of the intermediate portions of cores in 90 cast iron pipe molds, comprising pins adapted to pass through openings in the flask sections and to bear on the top, bottom and side of the core bar, said pins having tapered inner ends where traversing the space for the 95 molten metal and bearing on the core bar and having exposed outer ends, wedges for holding the top and bottom pins in engagement, a bracket adapted to be bolted to the drag section of the flask and having spaced 100 lugs provided with undercut faces opposite the exposed end of the side pin, and a wedge having a beveled edge and adapted to be driven in between the lugs and said pin to hold the same against the core bar.

In testimony, that I claim the foregoing as my own, I have hereto affixed my signature.

JAMES R. McWANE.
